H. M. Collins,

By Clarence O'Brien

Attorney

UNITED STATES PATENT OFFICE.

HATTIE M. COLLINS, OF LEE, MASSACHUSETTS.

VALVE-SPRING COMPRESSOR.

Application filed March 3, 1926. Serial No. 91,973.

This invention relates to a tool for compressing the springs arranged around the valve stems of internal combustion engine motors, and has for its primary object to substantially improve and simplify tools of this general character.

To the attainment of this end, my tool embodies novel structural elements that are so combined as to afford the ready association of the tool with respect to the spring and to be actuated by a socket or other wrench to compress the spring between the usual end cups, and the head of the motor to permit the withdrawal of the retaining pin and the consequent removal of the valve.

An additional object of the invention is to provide a tool of this character that will automatically lock itself in spring compressing condition in order that the hands of the mechanic may be employed for removing the pin after the spring has become compressed.

A further object resides in the provision of a tool that is of extremely simple construction and that may be operated by unskilled workmen and that is adapted to have associated therewith various sizes and shapes of spring cup engaging jaws for enabling the tools to be employed in the compressing of springs that surround the valve stems of various types of motors.

Other objects will become apparent as the nature of the invention is better understood, the same comprising the novel form, combination, and arrangement of parts herein-after more fully described, shown in the accompanying drawing and claimed.

In the drawings wherein like reference characters indicate corresponding parts throughout the various views:

Figure 1 is a fragmentary section through a conventional form of motor, the spring of the valve disclosed being shown in compressed condition through reason of my improved tool which is disclosed in side elevation.

Figure 2 is a top plan view of the tool.

Figure 3 is a longitudinal section of the same in collapsed condition.

Figure 4 is a perspective of the type of valve spring cup engaging jaw adapted to be employed in conjunction with the present tool.

Figure 5 is a fragmentary view partly in elevation and partly in cross section of a

preferred form of socket wrench that is to be employed in the operation of my tool, and.

Figure 6 is a fragmentary perspective of one of the bar members of the tool for more clearly disclosing the construction of the end thereof for receiving said valve spring cup jaw.

Now having particular reference to the drawings, my novel spring compressor constitutes the provision of a pair of metal bars 5 and 6 preferably of square shape in cross section that are arranged in superposed relation as clearly shown in Figures 1 and 3. The forward end of the lowermost bar 6 is forked as at 7 to permit of the engagement of the same over the valve stem A directly above the valve tappet guide B of the motor. The forward end of the uppermost bar 5 is formed with a rounded socket 8 for receiving the circular shank 9 of a semi-circular shaped jaw 10 that is formed with an inwardly extending flange 11 at its lower end, said jaw adapted to engage around the valve spring cup C that supports the lower end of the valve closing spring D of the motor, as disclosed in Figure 1. Said shank 9 of the jaw is provided adjacent the jaw end thereof with a lug 12 that is adapted for engagement within a slot 13 at the socketed end of the top bar 5 for preventing the turning of the jaw therein. At this point it may be well to state that a tool of this character is equipped with a large number of jaws of various sizes in order to accommodate the attachment of the bar to various sizes of spring retaining cups.

Pivoted within a vertical opening 14 in the lowermost bar 6 adjacent the forward end thereof as at 15 is the lower end of a metallic arm 16 that extends upwardly through an opening 17 in the uppermost bar 5, the rear edge of this arm being toothed as at 18 for cooperation with a cross strip 19 of metal that is embedded within the lower side of the bar 5 at the opening 17, the inner edge thereof engaging over said opening to be engaged by said teeth as clearly shown in Figure 3. Arranged within a channel 20 in the bar 5 rearwardly of the socket 8 in the forward end thereof is an expandable coil spring 21 that serves to normally maintain the arm in positive engagement with the strip 19 and consequently

retain the bars 5 and 6 in predetermined spaced relation as in Figure 1.

For guiding the outer ends of the bars 5 and 6 during the aforesaid spacing of the same, a vertical pin 22 extends upwardly from the bar 6 adjacent the rear end thereof and has sliding movement through an opening 23 in the bar 5 adjacent its ends. Furthermore said pin prevents the canting of the upper bar 5 with respect to the lower bar 6 when pressure is applied to the forward ends thereof during the contracting of the spring D which is brought about by the movement of said bars away from each other.

Arranged loosely in the lowermost bar 5 directly forwardly of the pivotal arm 16 is a cross pin 24 headed at one end as at 25 and being threaded at its opposite end to receive a nut 26. Toggle links 27-27 are rigidly secured at their lower ends to the opposite ends of said pin 24 inwardly of the head and nut 25 and 26 respectively, these links being interconnected at their upper ends by a cross pin 29 that rides upon the under surface of the upper bar 5 when the pin 24 is turned by reason of a socket wrench preferably of the type shown in Figure 5, that is adapted to be disposed over the head 25 of the pin as shown in Figure 2 for thus moving the upper bar 5 in an upward direction with respect to the lower bar 6 and consequently compressing the spring D in the manner as clearly disclosed in Figure 1.

Extending loosely through the lowermost bar 6 directly forwardly of the vertical pin 22 is a cross pin 30 connected to the opposite projecting ends of which are links 31-31 that extend upwardly along opposite sides of the uppermost bar 5 and are interconnected above said bar with a cross pin 32 that rides upon the top surface of the bar 5 during the movement of the same to and away from the lowermost bar 6. Said links 31-31 are connected to the toggle links 27-27 through reason of relatively elongated links 33-33 in order that as the toggle links 27 move in opposite directions, said links 31 will move in a complementary direction and in view of the cross pin 32 connecting said links 31, the uppermost bar 5 will be caused to move in a true horizontal plane with respect to the lowermost bar, and thus prevent the binding of the same upon the pin 22 which would otherwise result.

The adjacent sides of the bars 5 and 6 are formed with rounded notches 5' and 6' at their forward ends for the reception of the connecting pin 29 between the toggle links 27-27 when the bars are moved into engagement as disclosed in Figure 3.

Also, the upper edges of the connecting links 33-33 are notched as at 33' adjacent the links 31-31 for receiving the heads of

the cross pin 32 for permitting said bars to be arranged in the face to face relation as shown in said Figure 3.

In operation the tool while in collapsed condition is actuated as to engage the forked end 7 of the bar 6 over the valve stem A directly above the tapped guide B, and the jaw 10 beneath the valve spring cup C. A wrench is then applied to the nut 25 of the pin 24 and then turned downwardly for 75 rotating the pin 24 within the bar which rotation will obviously raise the toggle links 27-27. The pressure of the connecting pin 29 of said toggle links will force the upper bar 5 away from the bar 6 in true parallel 80 relation therewith for consequently compressing the spring and raising the cup C from off of the retaining pin E, thus permitting the same to be withdrawn. During the upward movement of the bar 5 with respect to the bar 6 the strip 19 of said bar 5 will ratchet over the teeth 18 of the pivotal arm 16 and be engaged within the teeth for retaining the bar in the position to which the same is moved, thus permitting the workmen to withdraw both hands from the tool, facilitating the use of the same in the retraction of the pin E.

Preferably the type of wrench employed in the turning of the pin 24 is as shown in Figures 1, 2 and 5, the same constituting the provision of a bar-like handle 35 upon the front end of which is slidably arranged a nut receiving socket member 36. At the forward end of a handle is a cross pin 37 adapted for engagement within cross slots in the forward side of the socket in order that the socket may be moved around the bar and retained in proper position by the action of an expansible coil spring 38 that surrounds the bar between the sockets and an abutment pin 39 arranged in said bar.

Even though I have herein shown and described my novel tool as comprising certain detail structural elements, it is nevertheless to be understood that minor changes may be made therein without effecting the spirit and scope of the appended claims.

Having thus described the invention, what I claim as new and desire to secure by Letters Patent is:—

1. A valve spring compressor of the class described comprising upper and lower bars arranged in superposed relation, an anchoring fork carried by the inner end of the lower bar for engagement with a stationary part of the engine, a removable jaw implement carried by the inner end of the upper bar, a rigid guide pin carried by the outer end of the lower bar and extending through a guide opening in the upper bar, a pin mounted for oscillation upon the intermediate portion of the lower bar, elevating and lowering toggle links rigidly fastened to said pin, a connecting pin be- 130

tween the upper ends of said toggle links in sliding contact with the underside of the said upper bar and retaining means cooperable with said bars.

- 5 2. A valve spring compressor of the class described comprising upper and lower bars arranged in superposed relation, an anchoring fork carried by the inner end of the lower bar for engagement with a stationary part 10 of the engine, a removable jaw implement carried by the inner end of the upper bar, a rigid guide pin carried by the outer end of the lower bar and extending through a guide opening in the upper bar, a pin 15 mounted for oscillation upon the intermediate portion of the lower bar, elevating and lowering toggle links rigidly fastened to said pin, a connecting pin between the upper ends of said toggle links in sliding 20 contact with the underside of said upper bar, and retaining means cooperable with said bars.
3. A valve spring compressor of the class described comprising upper and lower bars 25 arranged in superposed relation, an anchoring fork carried by the inner end of the lower bar for engagement with a stationary part of the engine, a removable jaw implement carried by the inner end of the upper 30 bar, a rigid guide pin carried by the outer end of the lower bar and extending through a guide opening in the upper bar, a pin mounted for oscillation upon the intermediate portion of the lower bar, elevating and 35 lowering toggle links rigidly fastened to said pin, a connecting pin between the upper ends of said toggle links in sliding contact with the underside of said upper bar,

and retaining means cooperable with said bars, said retaining means comprising a 40 toothed pawl pivotally mounted on the lower bar and extending upwardly through an opening in the upper bar, and a tooth engaging strip carried by said upper bar and located in said last named opening. 45

4. A valve spring compressor comprising a lower bar provided at its inner end with an anchoring fork, an upper bar superimposed upon said lower bar and provided at its inner end with a detachable spring cup 50 engaging jaw, a guide pin rigidly mounted on the outer end of the lower bar and extending slidably through a guide opening in the corresponding end of the upper bar, a cross pin mounted for oscillation upon the 55 lower bar, toggle links rigidly connected at their lower ends to said cross pin, a connecting pin between the upper ends of said toggle links in slidable contact with the underside of said upper bar, a second cross pin 60 mounted for oscillation upon said lower bar, additional toggle links connected with said second cross pin and extending up and above said top bar, a connecting pin between the upper extended ends and said second-named toggle links slidably contacting the upper side of the upper bar, connecting links between the respective toggle links, a keeper plate provided on said upper bar, a spring pressed and toothed latch carried 65 by the lower bar and extending upwardly through an opening in the upper bar and engageable with said keeper plate.

In testimony whereof I affix my signature.

HATTIE M. COLLINS.
